United States Patent

Des. 235,918
Patented July 15, 1975

235,918

RIFLESCOPE

Claus A. Huckenbeck, Sherman Oaks, Calif., assignor to
Bausch & Lomb Incorporated, Rochester, N.Y.

Filed Sept. 9, 1974, Ser. No. 503,938

Term of patent 14 years

Int. Cl. D16—06

U.S. Cl. D57—1 E

FIG. 1 is an elevation of the left side of the riflescope;
FIG. 2 is a top view on line 2—2 of FIG. 1;
FIG. 3 is a right-side view on line 3—3 of FIG. 2;
FIG. 4 is a bottom plan view on line 4—4 of FIG. 3;
FIG. 5 is an end view on line 5—5 of FIG. 1; and
FIG. 6 is an end view on line 6—6 of FIG. 1.

I claim:

The ornamental design for a riflescope, substantially
as shown and described.
